[57] CLAIM

The ornamental design for a flexible conduit insert puller, as shown and described.

DESCRIPTION

FIG. 1 is a front elevational view of a flexible conduit insert puller of the present invention;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof, shown in use; and,

FIG. 7 is a cross sectional view thereof, taken along line 7—7 of FIG. 5.

The broken line showing of the environment of the article in FIG. 6 is for illustrative purposes only and forms no part of the claimed design.
